UNITED STATES PATENT OFFICE.

JOHN J. ROLL, OF NATRONA, PENNSYLVANIA.

GRATE-FRONT AND FENDER.

SPECIFICATION forming part of Letters Patent No. 700,560, dated May 20, 1902.

Application filed January 28, 1902. Serial No. 91,629. (No model.)

To all whom it may concern:

Be it known that I, JOHN J. ROLL, a citizen of the United States of America, residing at Natrona, in the county of Allegheny and State 5 of Pennsylvania, have invented certain new and useful Improvements in Grate-Fronts and Fenders, of which the following is a specification, reference being had therein to the accompanying drawings.

10 This invention relates to certain new and useful improvements in fenders and fire-fronts applicable to open fireplaces, and has for its object a fender and fire-front which may be compactly telescoped when out of operation and still retain its relative position with relation to the open fireplace.

The invention has for its further object a device of the above-described character which when telescoped will still permit sufficient air 20 to enter beneath the grate, and when placed in its extended position will effectually prevent any air from entering above the grate.

The invention has for its still further object simple and efficient means as well as 25 economy in construction.

With the above and other objects in view the invention consists in the novel combination and arrangement of parts, to be herein-after more fully described, and specifically 30 pointed out in the claims.

In describing the invention in detail reference is had to the accompanying drawings, forming a part of this specification, and wherein like numerals of reference indicate 35 similar parts throughout the several views, in which—

Figure 1 is a front elevation of a fireplace provided with my improved fender or fire-front, showing the same in its telescoped position. Fig. 2 is a vertical sectional view thereof, taken on the line 2 2 of Fig. 1. Fig. 3 is a vertical sectional view, partly broken away, showing the cover in its inoperative position. Fig. 4 is a perspective view of the 45 uppermost section of the fender or fire-front. Fig. 5 is a transverse sectional view taken on the line 4 4 of Fig. 1. Fig. 6 is a vertical central sectional view of the fire-front in elevated position.

50 In the accompanying drawings, illustrating a practical embodiment of my invention, the reference-numeral 1 indicates the uppermost

section, having curved ends 2, which carry the T-heads 3, operating in vertical slots 4, formed in the end plates 5, having a connecting-plate 11 with the horizontal slot 12 therein. This T-head extends through vertical slots 4, and the head of the T engages the rear face of this plate 5, thereby preventing the uppermost section 1 from being removed. This 60 uppermost section carries a flange 7, bent at a substantial right angle, which engages a similarly-formed flange 8 on the upper end of the lowermost section 9, the lower portion 10 of which is bent in the opposite direction 65 to that assumed by the flange 8. A casing 11 is formed integral with the connecting-plate 11 and receives the top plate 13, the ends of which are bent downwardly, as at 14 70 15, in the same direction to form the depending flanges. This top plate 13 carries an operating-handle 16, which when the top plate is received within the casing 11 projects sufficiently within the slot 12 to enable the same to be readily grasped by the fingers and the 75 top plate drawn outwardly for the purpose to be hereinafter fully set forth. The end plates 5 have notches or seats 17 and 18, formed on their rear face, adapted to receive the head of the T carried by the uppermost section 1. Any 80 number of these seats may be provided and may be placed at various distances apart in order to enable as fine an adjustment of the draft as desired. The uppermost section 1 carries a handle 19, whereby the section may 85 be conveniently raised and lowered.

When it is desired to close the draft from above the grate, the section 1 is raised by means of the handle, thus causing its flange 7 to engage the flange 8 of the lowermost section 9 and raise the latter simultaneously therewith. When the sections have been raised to the desired height, the head of the T is caused to engage in either of the notches 17 or 18, according to the adjustment desired. 95 This can be accomplished by merely exerting a slight rearward pressure on the handle of the section 1. The top plate 13 is then raised by means of the handle, and the flange 14 thereof is brought into engagement with the 100 upper end of the section 1, the outward movement of the top plate being limited by means of the engagement of its flange 15 with the wall formed by the slot 12. When the de-

vice has assumed the position as shown in Fig. 6, it will be noted that practically all air is prevented from having egress above the grate, the flange 10 of the lowermost section 9 being substantially in alinement with the upper end of the plate 20.

It will be noted that various changes may be made in the details of construction without departing from the general spirit of my invention.

Having fully described my invention, what I claim as new, and desire to secure by Letters Patent, is—

1. In a device of the character described, 15 the combination with end plates having a connecting-plate, of sections carrying means for limiting their movement in relation to each other, a top plate normally resting in the rear of said connecting-plate and adapted to engage the uppermost section, and means for movably mounting said sections within the end plates, substantially as described.

2. In a fender and fire-front, the combination of end plates and a connecting-plate, of 25 an uppermost section carrying a flange and a lowermost section carrying a flange for engagement with the said flange of the uppermost section, and a second flange at its lower end, of a top plate movably secured at the 30 upper end of the connecting-plate adapted for engagement with said uppermost section, said uppermost section being movably mounted in the end plates, and means for adjusting the uppermost section, substantially as 35 described.

3. The combination with the end plates

having vertical slots therein and a connecting-plate having a horizontal slot therein, of a casing formed integral with said connecting-plate, a top plate carrying flanges secured 40 in said casing, an uppermost section carrying T-heads engaging in said vertical slots, a flange formed integral with the lower end thereof, and a lowermost section carrying a flange for engagement with the flange of the 45 uppermost section, and a flange on the lower end of said lowermost section, substantially as described.

4. The combination with a pair of end plates spaced apart and having vertical slots 50 formed therein, and a horizontal plate having a horizontal slot therein secured to the said end plates at their upper portions, of a casing formed integral with the said horizontal plate upon its rear face, a top plate having depending flanges at its opposite sides located within the said casing, sections formed with end flanges fitting in the said vertical slots, each of said sections carrying means for limiting their movement in relation to each 55 other, and adapted to telescope one within the other when lowered, said top plate adapted to be drawn outwardly and fit over the upper edge of the upper section, substantially as described.

In testimony whereof I affix my signature in the presence of two witnesses.

JOHN J. ROLL.
